INSERT FOR TILLS

Application filed July 12, 1929. Serial No. 377,764.

Our invention relates to trays having vertical walls forming compartments and more particularly to tills having compartments formed suitably for receiving cash, checks and the like, for example paper currency, and means for readjusting the dimensions of the compartments, the principal objects of the invention being to adapt a partitioned tray for receiving currency having smaller dimensions than the currency for which the compartments were originally designed, and to adapt an insert for adjusting tray space to receive currency.

Cashiers' tills, the drawers and trays used by tellers and other clerks in banks, and like institutions, are provided with compartments having suitable dimensions for receiving the paper currency. Recently currency of relatively smaller size has been issued and the trays, therefore, are not adapted to accommodate same for economical use of space and for convenient handling.

Further objects of our invention therefore are to adapt tills to accommodate currency of the new sizes, and to employ the differential spaces no longer required for currency in a compartment for receiving and storing items such as cards, stamps, pins, sponges and the like.

In accomplishing these and other objects of the invention, we have provided improved details of structure, the preferred forms of which are illustrated in the accompanying drawing, wherein:

Fig. 1 is a perspective view of portions of a cash register with the cash drawer in open position and our improved device mounted in two of the compartments of the drawer to constitute the structure a sanitary till.

Fig. 2 is a perspective view of the reducing element embodying our invention adapted to be mounted in a compartment to adjust the area thereof for smaller sized articles.

Fig. 3 is a plan view of a modified form of sanitary till in which the reducing elements comprise the compartments.

Fig. 4 is a perspective view of one of the elements forming the till illustrated in Fig. 3.

Referring in detail to the drawing:

1 designates generally a cash register and 2

a drawer comprising a tray movable into and out of the register and having vertical side walls 3, front and rear walls 4 and 5 and partitions 6 forming compartments 7 whereby the drawer may constitute a till to receive money.

The compartment 7 is originally adapted to contain notes of conventional size and is therefore much larger than necessary for containing notes 8 of the new issues.

We therefore provide a reducing insert 9 comprising a chamber member 10 having front and back walls 11 and 12 shorter than the partitions forming the lateral front and back walls of the compartment, side walls 13 and 14, and a wing or plate comprising an extended portion 15 of the side wall 13 adapted to extend in spaced relation with one side wall of the compartment when the side wall 14 of the chamber member engages another side wall of the compartment.

The width of the reducing element is adapted to adjust the width of the compartment to fit the new currency and the depth from front to rear of the chamber member is adapted to reduce the length of the compartment for a similar purpose. The front wall of the chamber member is provided with an aperture 16 through which a screw 17 may be extended for attaching the insert to the front wall of the compartment as illustrated in Fig. 3.

The reducing element will thus be retained in fixed position but to assure the stability of the rearwardly extending wing we preferably form a lateral extending flange or bar 18 on the free end of the wing having width equal substantially to the differential between the width of the old currency and the new, said lateral flange forming the rear end wall of a narrow compartment 19 in which cards, notes, blotters and the like may be deposited.

In order to provide accessibility for articles contained in the compartment we cut away the upper edge of the wing as at 20 to form a relatively shallow portion, so that the fingers of the operator may be passed into the compartment to grasp the upper edge portions of the articles contained therein.

The modified form of the insert illustrated

in Figs. 3 and 4, comprises a front wall member 11 adapted to be attached to the front wall of a drawer, an extended side wall comprising the portions 13 and 15 of the preferred form, and a rear wall member 21 provided with a laterally presented latching socket portion 22 for interlocking engagement with the side wall ear 18 of an adjacent insert. The rear wall member 21 may be spaced suitably from the front wall 11 for accommodating articles to be stored in the drawer.

A suitable number of inserts of appropriate width may be provided to fill the space between the sides of the drawer, or a drawer may be provided of suitable width to accommodate inserts of desired dimensions. The interlocking ears and sockets will latch the rear ends of the inserts to form a line of connected rear walls, the outer ends of which are respectively an ear and a socket portion engaging sides of the drawer.

One of the inserts may then be attached to the front wall of the drawer, preferably the end insert, by inserting a fastener 17 through the front wall 11 of the insert into the front wall of the drawer.

The modified form of insert may also include the chamber forming transverse wall 12, and the chamber side wall 14, for stabilizing the inserts, in which case the walls 12 and 21 are spaced conformably to the length of articles to be stored.

A second row of inserts may be installed back of the single row shown in Fig. 3, one of the inserts having its front wall attached to the rear wall 21 of the adjacent insert of the front row in the same manner as that employed for fastening the insert of the front row to the front wall of the drawer.

The inserts are vertically slidable into and out of latching relation with adjacent positioned inserts.

The reducing members thus may be assembled as illustrated in Fig. 3 for comprising compartment elements when positioned in a relatively large compartment or in a tray not initially provided with compartments, and thus forming recesses adapted for receiving currency.

The rearwardly extending side walls of the inserts are preferably tapered as at 23 to lessen the height of the terminal portion of the wall and of the flange or ear, to accommodate the inserts to drawers having projections in rear walls adjacent the upper edges thereof.

The chamber comprises a storage space for frequently used items, and is particularly adapted to receive a sponge to hold water for moistening the fingers of the used, for facilitating picking up of the currency and rendering moistening of the fingers by other and less sanitary means unnecessary.

What we claim and desire to secure by Letters Patent is:

1. An insert for reducing the size of a tray compartment, including a chamber portion adapted to be attached to one of the vertical walls of the compartment for reducing the length of the compartment, and a side plate extending rearwardly from said chamber portion in spaced relation with an adjacent vertical wall of the compartment for reducing the lateral dimensions of the compartment. 70

2. In combination with a tray having vertical walls forming a compartment including front and side walls, a chamber member having less width than said compartment, means for attaching the front wall of the chamber member to the front wall of the compartment, said member having an extended side wall adapted to extend in spaced relation with one of the side walls of said compartment and provided with a laterally projecting ear for spacing said wall from the compartment wall. 80

3. In combination with a tray having vertical walls, means including members each having parallel front and back walls and side walls adapted to extend in parallel relation to form compartments in the tray, and means on each of said side walls engageable with the adjacent member for retaining the members in compartment forming position. 90

4. In combination with a tray having vertical walls, means including members each having parallel front and back walls and side walls forming compartments in the tray, said side walls being extended beyond the back walls, and means on each of said extended side walls engageable with the adjacent member for retaining the members in compartment forming position. 100

5. An insert of the character described comprising a rear wall, a front attaching member and a side wall connecting the rear wall with the attaching member and provided with a lateral wing extending oppositely to the rear wall. 105

6. An insert of the character described, comprising parallel front and rear walls, a side wall, a lateral flange at the rear end of the side wall and a socket at the outer end of the rear wall to receive the flange of an adjacent insert. 110

7. An insert for tills comprising side and end walls, and an ear projecting laterally from one of said walls adapted to effect spacing of said side wall from the adjacent side wall of the till. 120

8. A device of the character described, including a side wall having lateral projections forming respectively an ear member and an end wall member, and means for attaching one of said members to a wall of a tray or the like for enabling the device to reduce the effective area of the tray. 125

9. An insert for tills comprising a side wall having an ear projecting laterally there- 130

from to engage the side wall of a till for spacing said insert side wall from the side wall of the till, and an end wall projecting from one end of said side wall, and means for securing said insert to the till.

5 10. An insert for tills comprising a side wall having an ear projecting laterally therefrom to engage the side wall of a till for spacing said insert side wall from the side wall of the till, and an end wall projecting from one end of said side wall oppositely to said ear, and means for securing said insert to one of the end walls of the till.

10 11. In combination with a tray having side walls forming a compartment, an insert comprising a chamber member including end walls and a side wall having a laterally projecting ear for spacing the side wall of the insert from the adjacent side wall of the tray, and means for attaching the insert to the tray with one of said end walls spaced from the adjacent end wall of the tray.

20 12. In combination with a tray having end, side and bottom walls, an insert including a vertical side wall provided with a cut-away portion and having a laterally projecting ear, and an end wall, and having an aperture to admit fastening means for securing said insert to one of the walls of the tray.

30 35 In testimony whereof we affix our signatures.

HENRY G. BEARD.
